SUPPLEMENTAL COLLAPSIBLE TABLE TOP

Joseph Martin Kelleghan, Flint, Mich.

Application December 11, 1946, Serial No. 715,533

8 Claims. (Cl. 311—106)

1

This invention relates to table tops and more particularly to table tops which can be disassembled or collapsed.

In the past, large game tables, such as poker tables, have been very large and cumbersome, and when not in use have required a great deal of storage space. This has proved to be impractical for people living in places with limited storage space and therefore many people who would desire such a large game table have not purchased the same because of the storage feature.

It is therefore the primary object of this invention to provide a large supplemental table top which can be quickly disassembled and stored as a relatively small package.

Other principal objects of this invention are: to provide a large table top which can be secured to and supported on a conventional card table; to provide a table top of the aforementioned type which is formed with a plurality of depressions therein adapted to receive complementally shaped serving trays or poker chips, cards, dice or the like; to provide a table top of the aforementioned type which is formed with a plurality of depressions therein for receiving ash trays and glass holders; to provide a table top of the aforementioned type which can be stacked when not in use into a neat, compact package; and to provide a table top of the aforementioned type which is especially attractive in appearance, simple to assemble and disassemble, and rugged in construction.

These and other objects of this invention will become apparent from the following detailed description taken in conjunction with the accompanying drawings in which:

Figure 1 is a perspective view of one embodiment of this invention;

Fig. 2 is an enlarged partial plan view of the structure illustrated in Fig. 1;

Fig. 3 is an exploded plan view of a portion of the structure shown in Fig. 2;

Fig. 4 is an enlarged cross-sectional view taken along the line 4—4 of Fig. 3;

Fig. 5 is an enlarged cross-sectional view taken along the line 5—5 of Fig. 2;

Fig. 6 is a cross-sectional view taken along the line 6—6 of Fig. 5;

Fig. 7 is a cross-sectional view taken along the line 7—7 of Fig. 2;

Fig. 8 is a cross-sectional view taken along the line 8—8 of Fig. 2;

Fig. 9 is a cross-sectional view taken along the line 9—9 of Fig. 2;

Fig. 10 is a cross-sectional view of the struc-

ture illustrated in Fig. 7, taken along the line 10—10 thereof;

Fig. 11 is a perspective view of one embodiment of an ash tray for use with the table top of this invention;

Fig. 12 is a perspective view of one embodiment of a glass holder for use with the table top of this invention;

Fig. 13 is a perspective view of one embodiment of a serving tray for use with the table top of this invention; and

Fig. 14 is a view, partially in elevation and partially in section, of a further embodiment of the invention.

15 Referring now to the drawings, and more particularly to Fig. 1, it will be seen that the table top of this invention, generally indicated at 15, comprises four peripheral elements 17, 19, 21 and 23 which, when interconnected, form an octagon 20 shaped outer portion for the table top, and a central table top portion 25 supported by said peripheral elements, as will be hereinafter brought out in detail. The entire table top 15 can be supported on a conventional card table, generally indicated at 27, in a manner which will be brought out hereinafter in detail.

Each of the peripheral elements 17, 19, 21 and 23 is identical in construction, and similar part numbers for one, therefore, refer to similar parts in all four of the elements. For purposes of description, the peripheral element 17 will be described in detail. This element is formed by a stamping operation on a single piece of sheet metal or by molding when made of plastic, metal, or other moldable material. As can be seen in Fig. 2, the peripheral element 17 is formed with two substantially like portions 18 and 20 disposed in angular relation so that the included angle is substantially 135°. The element is provided on its upper surface with a pair of similarly shaped

30 depressions or trays 29 and 31, one in each of the like portions 18 and 20, respectively. These depressions are of a suitable size and shape to receive a serving tray 33 illustrated in Fig. 13. The depressions 29 and 31 can be used to retain poker chips, cards, dice or the like when the table top 23 is being used without the serving tray. Adjacent to each side of the depression 29, is a pair of depressions 35 and 37 of octagon or other shape which are adapted to receive complementally shaped ash trays 39, shown in detail in Fig. 11. Inwardly of the ash tray receiving portions 35 and 37, the upper surface of the peripheral element 17 is provided with depressions

45 55 41 and 43, respectively, which are of an octagon

or other shape and which have an opening 45 extending through the bottom wall thereof. The depressions 41 and 43, with the opening 45 therethrough, are adapted to receive a glass holder 49 shown in detail in Fig. 12. This glass holder 49 is of an annular shape and has a flange 51 around the upper end thereof, which flange is adapted to be supported by the bottom wall of the depressions 41 and 43, adjacent to the opening 45, with the body of the holder 49 extending through the opening 45.

The outer edge of the peripheral element 17 is formed with a rolled flange 53 which extends along the entire length of the element. Adjacent to the left end of the peripheral element 17, the rounded flange 53 is provided with an opening 55 therethrough into which a lock element, generally designated at 57, is inserted. The lock element 57 comprises a handle 59 pivotally mounted on a shaft portion 61. The shaft portion 61 has a cap element 63 secured thereto adjacent to the handle 59 which is adapted to abut against the outside of the flange 53. The portion of the shaft 61 positioned inwardly of the flange 53 is provided with a washer 65 which prevents withdrawal of the lock element 57 through the opening 55. The inner end of the shaft 61 is formed with a hub 67 thereon which has a bayonet type slot arrangement 68 therein which is adapted to engage a wire element on the adjacent peripheral element 23 to lock the elements 17 and 23 together, as will be hereinafter described in detail.

Immediately inwardly of the depressions 31 and 33, the top surface of the peripheral element 17 is provided with a raised bead 71 which extends from the left-hand end of the peripheral element to a point adjacent to the right-hand end thereof. Extending inwardly from the lower inner edge of the bead 71 is a horizontal flange 73. Depending vertically from the horizontal flange at a point inwardly of the depression 29, is a tab element 74, the use of which will be described later. Adjacent to the left-hand end of the peripheral element 17, at the corner 75 where the bead 71 and peripheral element 17 change direction to form another side of the octagonal periphery of the table top, the bead 71 is widened to form a horizontal triangular flange or surface 77 in extension of the top surface of the bead 71 on both sides of the point 75. Below the flange 77, the side wall of the bead 71 is cut out to provide a slot 79 and the horizontal flange 73 immediately inwardly of the slot 79 is offset downwardly, as at 81, to increase the distance between the upper flange 77 and the lower flange 73, as illustrated in Fig. 10. The portion of the bead 71 immediately inwardly of the glass holder depression 43, at the corner 83 where the direction of the bead changes to form another side of the octagon, is also provided with a triangularly shaped upper flange 85 below which the side wall of the bead 71 is cut away to provide a slot 87. It will be noted that the center of both the flange 85 and flange 77 is upwardly flared to provide a bell mouth 89 for a use which will be hereinafter described. The bead portion 71 on the right-hand end of the peripheral element 17 is, as illustrated in Fig. 4, stepped down and tapered downwardly and outwardly as at 91 for a reason which will be hereinafter brought out.

The right-hand end of the rolled outer flange 53 of the peripheral element 17 is provided with a vertical elongated slot 93, and a diagonal wire element 95 is secured to the inner surface of the flange 53 on opposite sides of the slot 93 such

as by rivets 97, so that the wire element extends across the face of the vertical slot 93. The wire element 95 is adapted to be gripped by the bayonet slotted hub 67 on the lock element 55 of the adjacent peripheral element 17. When the two peripheral elements 17 and 23 are interconnected, it will readily appear that the lock element 51 can be turned to engage the wire element 95 and draw the two peripheral elements together and lock them securely to each other. The lock is readily released when it is desired to disengage the various peripheral elements and is not limited to the particular construction herein illustrated and described, as other elements, known in the art to be suitable, may be substituted therefor.

Inwardly of the flange 53, the right hand of the peripheral element 17 is provided with a depressed portion 99 which is provided with a circular opening 101 therein, intermediate its inner 20 and outer ends, which is adapted, when the peripheral elements 17 and 19 are assembled, to be aligned with the glass holder opening 45 in the adjacent peripheral element 19. The inner end of the depressed portion 99 extends upwardly 25 to form a tongue 103 which is separated from the flange 13 by an arcuate slot 105 for a purpose which will be hereinafter brought out.

To assemble the peripheral element 17 to the peripheral element 19, the left-hand end of the peripheral element 19 is laid over the top of the depressed portion 99 of the element 17 and the tongue 103 of the element 17 is inserted inwardly through the slot 79 in the element 19 so as to overlap the horizontal flange 13 thereon. 30 It will be noted that the left-hand end of the bead 71 of the element 19 rests over the tapered portion 91 on the right end of the bead 71 of the element 17. In this way, a pivotal action is 35 permitted between the two elements which, as 40 will be hereinafter brought out, is necessary for easy assembly and disassembly of the two parts. When the element 19 is so lapped over the element 17, the lock mechanism 57 on the element 19 is then forced inwardly into engagement with the wire element 95 on the inner surface of the flange 53 of the element 17. The lock element 57 is then turned to engage the wire element in the bayonet slot arrangement in the lock element and the members are then firmly locked together. When this is accomplished, it will be 45 noted that the glass holder opening 45 in the element 19 is aligned with the opening 101 in the depressed portion 99 of the element 17. The glass holder 49 can then be inserted through the two openings 45 and 101 to further add to the rigidity of the connection between the two members. The peripheral element 21 can then be similarly connected to the peripheral element 19, and the peripheral element 23 can then 50 be interconnected in the same manner with the elements 17 and 21 to form a completed interconnected outer portion for the table top.

The central table top portion 25 which, as 55 illustrated in Fig. 2, is foldable along the center line 107, likewise allowing it to be collapsed into a fairly small package when it is shipped or stored, has an outer periphery in the shape of an octagon, similar to the shape of the inner periphery of the table top outer portion. The central table top portion 25 can be made of any 60 suitable material but preferably is made of a rigid material with a felt covering. To connect the central portion 25 to the outer portion formed by the interconnected peripheral elements, each 65 of the corners of the octagonal periphery of the

central portion is inserted within its respective slot 79 or 81 formed in the bead 71 along the entire inner periphery of the outer table top portion as the elements are assembled together thereabout. The bell mouths 89 formed on each of the flanges 85 and 77, respectively, allow the corners of the central table top portion 25 to be easily inserted into the slots and reduce the danger of tearing the felt on top of the portion 25. If desired, the felt covering at each corner of the central portion 25 can be covered with a thin protector plate of metal or other material so as to completely eliminate the danger of tearing the felt when the central portion corners are inserted in the outer portion slots.

As each of the elements 17, 19, 21 and 23 is assembled to an adjacent element, the slots 79 and 81 thereof are advanced over the adjacent corners of the central table top portion 25. As pointed out hereinabove, the connection between the elements is such as to permit a pivoted action to occur therebetween so that they can be drawn inwardly about the central table top portion due to the arcuate shape of the end of the slot 105. The table top portion will be supported on the horizontal flange 73 formed inwardly of the bead 71 and will be retained in fixed relation thereto by the engagement of its corners within the slots 79 and 81.

To retain the table top 15 on the card table 27, the tab elements 74 provided on the inner edge of each of the peripheral elements and oppositely disposed from each other, engage each side edge of the table. The table top 15 cannot then be moved with respect to the card table unless it is lifted upwardly therefrom.

To disassemble the table top 15, the serving trays, ash tray and glass holders are removed and the lock elements 57 are then unlocked and, due to the tapered ends 91 on the beads 71 adjacent to the tongues 103, each peripheral element can then be swung out of engagement with the central table top portion 25 and with its adjacent element because of the presence of the arcuate end of the slot 105. The central portion 25 can then be folded and the peripheral elements stacked together. The entire table top can then be transported and stored as a relatively small package.

In the embodiment illustrated in Fig. 14, the table top 15 is illustrated as mounted upon its own table legs 111. The tabs 74 are provided with an elongated vertical slot 109 and the four legs 111 are provided at their upper ends with a vertical slot 113 adapted to receive the tab 74 therein. The legs are then secured to the tabs by inserting a bolt 115 through the lateral openings 110 in legs 111 and through the slots 109 in the tabs 74. A thumb nut 117 is then screwed onto the threaded ends of the bolt and tightened against the outer surface of the leg to rigidly secure the legs to the tabs. Intermediate the upper and lower ends of the legs 111, horizontal supporting bars 119 are provided which are connected at their opposite ends by hinges 121 to the adjacent legs. Each bar 119 is split at its center, as at 123, and a hinge 125 is provided to hingedly connect the two split halves of each bar 119. When the legs are removed from the table top 15, the bars 119 may be folded upwardly at their center to allow the four legs to be drawn together into a small compact package for storage along with the other compact parts of the disassembled table top.

While the invention has been illustrated and described with reference to a game table, it is to be understood that the invention is not so restricted and that the table may be used for picnics, camping trips and the like when suitable dishes, cups and trays are provided, such as herein shown, from which food may be served.

What is claimed is:

1. In a collapsible table top, a plurality of peripheral elements forming the outer portion thereof, each of said peripheral elements having an inwardly extending horizontal flange formed on the inner periphery thereof, a central table top portion positioned on and supported by said horizontal flanges, said table top portion having a plurality of corners, a bead formed adjacent to said horizontal flange and having slots therein to receive the corners of said central table top portion and secure it to said peripheral elements, an underlapping portion formed on the opposite end of each of said peripheral elements which underlaps the opposite end of an adjacent element, and a tongue on said underlapping portion which projects through one of said slots and overlaps said horizontal flange.
2. In a collapsible table top, a plurality of peripheral elements forming the outer portion thereof, each of said peripheral elements having an inwardly extending horizontal flange formed on the inner periphery thereof, a central table top portion positioned on and supported by said horizontal flanges, said table top portion having a plurality of corners, a bead formed adjacent to said horizontal flange and having slots therein to receive a corner of said central top portion and secure it to said peripheral elements, an underlapping portion formed on the opposite end of each of said peripheral elements which underlaps the opposite end of an adjacent element, a tongue on said underlapping portion which projects through one of said slots and overlaps said horizontal flange, and lock means for releasably securing each of said peripheral elements to its adjacent overlapping peripheral element.
3. In a collapsible table top, a peripheral element formed of a single stamping a plurality of which form the outer peripheral portion of the top, one end of each element being formed to overlie the opposite end of the element and to interlock therewith so that the first end of one element may overlie the other end of an adjacent element and to interlock therewith to form a rigid peripheral assembly.
4. In a collapsible table top, a peripheral element formed of a single stamping a plurality of which form the outer peripheral portion of the top, one end of each element being formed to overlie the opposite end of the element and to interlock therewith so that the first end of one element may overlie the other end of an adjacent element and to interlock therewith to form a rigid peripheral assembly, and releasable locking members one located at each of said ends to interlock with an associated member of an adjacent element.
5. In a collapsible table top, a peripheral element formed of a single stamping a plurality of which form the outer peripheral portion of the top, one end of each element being formed to overlie the opposite end of the element and to interlock therewith so that the first end of one element may overlie the other end of an adjacent element and to interlock therewith to form a rigid peripheral assembly, releasable locking members one located at each of said ends to in-

terlock with an associated member of an adjacent element, and a central top portion having projecting corners extending into the inner peripheral edge of the assembled elements to be supported thereby.

6. A collapsible table top including four like elements having opposite end portions which are capable of interlocking and overlying each other so that one end of one element may interlock and overlie the other end of an adjacent element, the inner peripheral edge of said elements having slots, and a central table top portion having projecting portions which extend within said slots to be supported by said elements.

7. A collapsible table top including four like interconnecting peripheral elements having portions of substantially 135° relationship to each other, the ends of said portions being formed to interlock and overlie each other so that one end of one element may overlie and interlock with the opposite end of an adjacent element, the inner peripheral edge of each member having at one end and at the central portion a slot, and a central table top portion of octagonal shape having the corner portions inserted in said slots when the elements are assembled therearound.

8. A collapsible table top including four like interconnecting peripheral elements having portions of substantially 135° relationship to each other, the ends of said portions being formed to interlock and overlie each other so that one end of one element may overlie and interlock with the opposite end of an adjacent element, the

inner peripheral edge of each member having at one end and at the central portion a slot, a central table top portion of octagonal shape having the corner portions inserted in said slots when the elements are assembled therearound, and complementary locking members carried at opposite ends of the element so that the overlying interlocked portions may be locked together by said members.
